CARBON SCRAPER FOR PISTON RING GROOVES

Original Filed Aug. 30, 1926

Patented Jan. 3, 1928.

1,654,851

UNITED STATES PATENT OFFICE.

HOMER S. ALBERT, OF MERCER, PENNSYLVANIA.

CARBON SCRAPER FOR PISTON-RING GROOVES.

Application filed August 30, 1926, Serial No. 132,519. Renewed June 30, 1927.

The invention aims to provide a new and improved scraper for the purpose of removing carbon from piston ring grooves, the device being of such nature that it is simple and inexpensive, yet is efficient and very desirable for use upon pistons of numerous sizes.

With the foregoing in view, the invention resides in the novel subject matter hereinabove described and claimed, the description being supplemented by the accompanying drawing.

Fig. 1 is an elevation of the tool and a sectional view through a piston showing the manner of using the device in cleaning the carbon from a ring groove of said piston.

Fig. 2 is an edge view of the tool.

Fig. 3 is a transverse sectional view on line 3—3 of Fig. 1.

Fig. 4 is a disassembled perspective view of certain elements of the device, to be hereinafter described.

In the form of construction selected for illustration in the present application, the numerals 5 and 6 designate two flat metal bars disposed in crossed relation and pivoted together at 7, the portions of the bars in advance of the pivot being shaped to straddle a piston P, said portion of one of the bars being then receivable in any of the ring grooves G of said piston, while carbon scraping means carried by said portion of the other bar, is then also engageable with the groove. Thus, by grasping the rear or handle portions of the bars 5 and 6 and turning the device about the piston or turning the latter within the device, all carbon may be quickly and easily removed from the ring groove, and after cleaning one groove, the other grooves may be successively cleaned in the same manner.

The numeral 8 designates a V-shaped scraper whose ends are suitably sharpened at 9 to engage the bottoms and sides of the ring grooves. This scraper lies upon one flat side of the bar 5, at the front end of the latter and the two ends of said scraper project inwardly from the inner edge of said bar 5. A metal plate 10 contacts with the side of the scraper 8, remote from the side which contacts with the bar 5, said plate and bar being formed with registering openings 11 and 12. A screw 13 or some analogous fastener passes through these openings and is received in the crotch of the scraper 8. At one end, the plate 10 has

corner portions 14 bent laterally to engage the outer edge of the scraper 8 and prevent transverse sliding of the latter away from the screw 13. The opposite end of the plate 10 is bent laterally in the same direction as the corners or flanges 14, to provide an additional flange 15.

This flange extends between the two end portions of the scraper 8 and abuts the inner edges of said end portions, and said flange also abuts the inner edge of the bar 5. Thus, turning of the plate 10 with respect to the bar 5 is prevented and any turning of the scraper with respect to said plate is prevented, and as the flanges 14 hold the scraper 8 against movement in one direction, and the screw 13 holds it against movement in the other direction, it will be seen that the scraper is rigidly yet detachably secured to the bar 5.

With each tool, a set of scrapers of different thicknesses, may be furnished. Thus, a scraper of the necessary thickness for any width of ring groove, may be applied to the bar 5, and quick and easy interchange from a scraper of one thickness to one of another, may be effected.

Excellent results have been obtained from the details disclosed and they are therefore preferably followed. However, within the scope of the invention as claimed, variations may be made.

I claim:

1. In a carbon scraper for piston ring grooves, a scraper-carrying member, a V-shaped scraper lying against said carrying member and having its ends projecting therefrom, a plate lying against the side of said scraper remote from the carrying member, a fastener passing through said plate and said carrying member and disposed in the crotch of said scraper, and means on said plate abutting the outer edge of said scraper to hold it against sliding with respect to said plate.

2. In a carbon scraper for piston ring grooves, a scraper-carrying member, a V-shaped scraper lying against said carrying member and having its ends projecting therefrom, a plate lying against the side of said scraper remote from the carrying member, a fastener passing through said plate and said carrying member and disposed in the crotch of said scraper, means on said plate abutting the outer edge of said scraper to prevent sliding of the latter with respect to the plate, and

means on said plate abutting an edge of said carrying member to prevent turning of the plate about said fastener.

3. A structure as specified in claim 2; said edge-abutting means consisting of flanges bent laterally from said plate.

4. A structure as specified in claim 2; said edge-abutting means consisting of flanges

bent laterally from said plate, the flange which abuts said edge of said carrying member having its ends in contact with the inner edge of the scraper to prevent turning of the latter about said fastener.

In testimony whereof I have hereunto affixed my signature.

HOMER S. ALBERT.
